UNITED STATES PATENT OFFICE.

ORIN BENNETT, OF PLACERVILLE, CALIFORNIA.

TYPE-WRITING MACHINE.

1,115,275.

Specification of Letters Patent. Patented Oct. 27, 1914.

Application filed March 26, 1914. Serial No. 827,279.

To all whom it may concern:

Be it known that I, ORIN BENNETT, a citizen of the United States, residing at Placerville, in the county of Eldorado and State of California, have invented certain new and useful Improvements in Type-Writing Machines; and I do declare the following to be a clear, full, and exact description of the same, such as will enable others skilled in the art to which it appertains to make and use the same, reference being had to the accompanying drawings, and to the characters of reference marked thereon, which form a part of this application.

This invention relates to improvements in typewriting machines of the type commonly used for manually performing typewriting, the object of the invention being to produce a mechanism whereby the impression of the type or rather the type movement will be operated by an independent mechanical means rather than by the direct power of the operator, which mechanical operating means will be released for operation by the movement of the keys of the typewriter and which after such release will thereafter automatically perform the operation of striking the type keys against the paper or other material to make the impression of the type thereon. This key operating mechanism will be capable of operating with a very slight touch from the operator so that no physical power will be necessary in order to operate the type bars. By means of this structure the impression made by the type will always be substantially the same; the alinement can be kept absolutely perfect and also a great many manifold copies can be made more easily and efficiently than where the impression is taken solely by means of the physical strength of the operator.

A further object of the invention is to produce an electrically controlled means for operating the entire structure immediately upon the operating keys being touched by the operator, the balance of the operation being then carried on by magnetic attraction. This latter feature however may or may not be used as the mechanism can be operated with or without the same as may be found desirable.

A further object of the invention is to produce a simple and inexpensive device and yet one which will be exceedingly effective for the purposes for which it is designed.

These objects, I accomplish by means of

such structure and relative arrangement of the parts as will fully appear by a perusal of the following specification and claims.

On the drawings, similar characters of reference indicate corresponding parts in the several views.

Figure 1 is a top plan view of one operating key and of the mechanical impression mechanism connected therewith which illustrates the operation of all the keys, hence I have not confused the matter by showing all the keys, each of which would merely be a duplicate of the other. Fig. 2 is a side elevation, partly in section, of the subject matter shown in Fig. 1, showing the entire mechanism in inactive position. Fig. 3 is a side elevation of the mechanical impression mechanism showing it in the same position shown in Fig. 2 but partly broken out to show the internal construction thereof. Fig. 4 is a front elevation of the type rack showing the position of the mechanical impression mechanism with respect thereto. Fig. 5 is a side elevation of the mechanical impression mechanism in inactive position. Fig. 6 is a rear elevation of the same. Fig. 7 is a side elevation of the same showing it just prior to operation. Fig. 8 is a sectional view showing a means for connecting a key bar with an operating shaft. Fig. 9 is a side elevation of the type rack operating cams.

Referring now more particularly to the characters of reference on the drawings, the numeral 1 designates the stand or frame of the device which of course can be of any suitable desired structure and suitably disposed therein by means of supporting brackets 2 or otherwise is the platen 3 mounted adjacent the type bars 10 and 95 adapted to be provided in practice with suitable operating mechanism here not shown for the reason that I do not make any claim in this application to that structure. It might be well to note also at this time that the device will be provided with a suitable carriage, escapement and all other necessary mechanism to provide successful operation, but these several mechanisms will be made the subject matter of specific applications for patent, hence I do not here show, describe or claim any of them, this application being confined solely to the mechanism whereby the mechanical impression is derived.

My improved mechanical impression mechanism involves a single driving or tap-

ping hammer which actuates the typing bar, there being but the single driving or tapping hammer which operates all of the type bars and hence it becomes necessary to provide a mechanism for bringing each individual type bar into alinement with such driving or tapping hammer in order that the impression of the type may always be made at the same point with respect to the complete structure of the machine so as to place the type in successive alinement on the paper or other material. To this end then my mechanism embodies in its complete operation two structures, namely, the type carriage and the mechanism for operating the same to aline individual type bars with the driving or tapping hammer and the second, the mechanical impression mechanism whereby the tapping hammer is operated to cause the type bar to move to bring the type into contact with the paper or other material. I will therefore describe these two mechanisms separately and describe first, the type carriage and operating mechanism: This structure embodies first a quadrant-shaped carriage frame 5 pivoted, as at 6, in any suitable frame and provided with a quadrant-shaped counter weighted frame 7 below the pivotal point 6, which counter weighted mechanism acts to help maintain the type carriage 5 in normal vertical position. Within the carriage frame 5 is a semi-circular shaft 8 on which are pivotally mounted, as at 9, individual type bars 10. The upper end of each of the type bars 10 projects through a guide slot 11 in the outer periphery of the frame and is provided at its extreme upper end with the type 12. In the drawings shown herewith, I show three of these type 12, one for the small letters, one for the capital letters and one for other indicating data, which three types may be brought into position in proper alinement by means of shifting the carriage 5 up or down, but this action is a separate and independent invention which is not here shown or claimed.

The vertical center line of the normal position of the carriage 5 will be the point at which the impression will be taken from the type and therefore it is necessary that such carriage 5 be capable of being swung from side to side in order to bring the several individual type bars into proper alinement with said center line in order to be actuated by the tapping or driving hammer which strikes the type bar and brings the type in contact with the paper or other material on the platen 3 and this mechanism comprises first the shaft 6 which is suitably journaled adjacent the member 5 in a frame 13 or any other suitable member, which shaft 6 projects to a point near the front of the typewriting machine where it is again journaled in any suitable manner, as

at 14. Secured to the said shaft 6, at any suitable point, is a projecting arm 15 connected by a toggle joint 16 with a downwardly projecting link 17 yoked as at 18 over a rod 19 journaled at each end in an arm 20, such arms 20 being turnably mounted on a shaft 21 and each being provided with an obliquely projecting arm 22 carrying in their outer ends another rod 23 disposed parallel with the rod 19 and in the same vertical plane therewith. 75

Disposed approximately midway between the rods 19 and 23 is a shaft 24 suitably journaled at its ends, as at 25. Secured on the shaft 24 is a cam 26 curved at its upper end and normally engaging the rod 19 when the machine is in inactive position for the purpose of fixing the normal true position of the arms 20 and 22 and the rods 19 and 23 carried thereby. 80

For each key of the typewriter I provide a cam 27 secured to the shaft 24, each of said cams having two oppositely disposed curved surfaces 28 and 29 respectively, capable of being brought into engagement with cams 30 and 31 respectively, secured to the rods 19 and 23 for the purpose of taking up wear. This adjustment consists of collars 30^a and 31^a provided with set screws 30^b and 31^b whereby said cams 30 and 31 are capable of being adjustably set on said rods 19 and 23. There is one cam 27 for each operating key on the machine and the curvatures of the surfaces 28 and 29 are varied so that with the movement of the cams 27 with the shaft 24, the surfaces 28 engaging their corresponding cam 30 will lift the rod 19 and incidentally the arm 20 and its corresponding arm 22 accordingly. The distance of each lift will vary with the various keys due to the difference of the curvatures of the surfaces 28 and 29. The purpose of the spaced arms 22 with the cams 28 and 29 moving between the corresponding rods 19 and 23 is so that the movement will always be exactly the same. The movement of the said rod 19 operates the link 17 and incidentally the arm 15 to turn the shaft 6. The movement of said shaft 6 swings the type carriage 5 to such a point as will bring the type bar 10 corresponding to the key which has been operated into the center alinement for being operated by the impression mechanism. 100 110 115

The cams 17 receive their movement from the keys 32 by means of the following structure, namely: On each cam 27 is a set of gears 33 which in turn mesh with a set of gears 34 on a bar 35, which bar has an eye 36 turnably mounted on the shaft 21, said eye 36 having a slotted portion 37, the bottom of such slotted portion normally engaging a key 38 set into the shaft 21 whereby with the movement of the said rod 35 the shaft 21 will likewise be moved. The rea- 120 125 130

son of this key and slot structure is that when a plurality of the rods 35 are disposed in the machine it is only desired that the movement of one will affect the shaft 21, the others remaining idle in the meantime, this being permitted of by reason of the keys 38 moving through the slots 37 in the several bars 35. The cams 27 are similarly secured to the shaft 24 (see Fig. 9).
 10 The eye 36 is provided with another branching bar 39 which is the key bar which is suitably bent into any desired shape to properly position the key 32. Projecting downwardly from the bar 35 is a small arm 40 and projecting downwardly from the bar 39 is a small arm 41. On the bottom of the member 40 is a contact plate 42 having a projecting finger member 43. On the bottom of the member 41 is a contact plate 44 while 45 designates a wire connected with the member 41 and running through a source of electrical energy 46 and back to connection with an electromagnet 47 positioned immediately below the member 40 and having a projecting spring contact member 48 positioned immediately below the member 41. When the key 32 is pressed, this moves the bar 39 and incidentally the bar 35 downwardly moving the shaft 21 in the manner described, which movement of the shaft 21 will operate certain other mechanism to be hereinafter described.
 15 With reference to the particular structure now being referred to, namely, the type carriage 5, the movement of the members 39 and 35 brings the contact plate 40 into engagement with the plate 48 thus electrifying the magnet 47 which then attracts the plate 42, the balance of the movement of the bars 39 and 35 being then continued by means of this electromagnetic attraction which continues until the finger member 43 engages the spring contact member 48 breaking this connection with the member 44 and allowing 20 the electromagnet to become dead, when a spring 49 moves the parts back to position, this spring 49 bearing against a projecting lever 50 on the shaft 21, which lever likewise performs other functions to be hereinafter described. With the downward movement of the bar 35 the gear 34 engages the gear 33 moving the cam 27 into engagement, as described, with the bars 19 and 23 simultaneously moving the cam 26 out of engagement 25 with such bar 19. This movement of the bar 19 then, in the manner set forth above, throws the type carriage 5 to bring the proper type bar corresponding to that key which has been depressed into center alignment, as above noted, and when this is done the driving or tapping hammer is actuated to strike the type bar and drive the type into contact with the platen 3 by means of the following structure and operation, 30 namely: On the lever 50 is a projecting

spring finger member 51 having a spring 52 holding the same in normal contact with a lug 53 on a dog 54. This dog 54 is provided with a pair of branches 55 pivotally mounted, as at 56, to the lower end of the driving 70 or tapping hammer 57 which is provided with a head 58 disposed at the normal center line of the carriage 5 to be alined with which everyone of the type bars is to be swung to said center line with the operation 75 of the said carriage 5 as above described. The lower end of the member 57 is provided with a pair of branches 59 in which is pivotally swung a catch 60 having a rearwardly projecting finger member 61, which finger member 61 is movable in a slot 62 of a slotted guide 63 and adapted to strike on an adjustable stop member 64 on said guide 63 to limit the movement of the catch 60 for a purpose as will presently appear. The said 80 guide member 64 also is provided with an upper stop end 65 against which the lower end of the member 57 rests when in normal inactive position, such member 57 being pivotally mounted by means of the pins 56 90 in supporting brackets 66. Mounted in a bracket 67 beneath the bracket 66 is a coiled spring 68 which is secured to the bottom of the dog 54.
 85 In practice, when the shaft is moved by means of the mechanism heretofore described, this causes the lever 50 to describe an arc upwardly which carries the member 51 also upwardly. The movement of the said member 51 engaging with the notch 100 53 moves the dog 54 on its pivotal connection 56 and tends to contract or wind up the spring 68. This movement continues until a notch 69 on the catch 60 engages a shoulder 70 on the dog 54. The movement 105 then continues until a small lug 71 on the dog 54 comes into contact with the member 51 by reason of the arc movement imparted to such dog 54. When this contact of the members 71 and 51 occurs, the member 51 110 is thrown out of engagement with the notch 53 and the expansion or unwinding of the spring 68 then gives the dog 54 a sudden jerk backwardly. This backward movement of said member 54 then is likewise imparted to the member 60 by reason of the engagement of the portions 69 and 70, this engagement being maintained by a small spring 72. By reason of this engagement and also by reason of the fact that the 115 member 60 is pivotally mounted on the end of the member 57, the entire movement actuated by the spring 68 will be imparted to the member 57 giving such member a quick sudden movement to drive the portion 58 120 into engagement with the type bar 10, thus throwing such type bar forward to bring the type 12 into engagement with the platen 3. The instant the member 58 strikes the type bar, the action of the spring 68 is 130

over and the member 70 has pulled loose from engagement with the member 69 and all the parts then drop back into normal position, the spring 52 again forcing the member 51 into engagement with the notch 53. The forward movement of the members 51 and 58 is limited by the finger member 61 striking the adjustable stop 64 and as has been before noted, the normal position of the member 57 is maintained by its engagement with the stop member 65.

When the above operation is completed, the spring 49 acting against the lever 50 moves the shaft 21 back to normal position 15 which, through the medium of the connections described, returns the type carriage and all the co-acting parts back to normal inactive position. The type bar throws back to normal position in the type carriage 5 by 20 means of the rebound given to the same with its impact against the rubber platen 3.

From the foregoing description it will be readily seen that I have produced such a device as substantially fulfills the objects of 25 the invention as set forth herein.

While this specification sets forth in detail the present and preferred construction of the device, still in practice, such deviations from such detail may be resorted to as 30 do not form a departure from the spirit of the invention.

Having thus described my invention what I claim as new and useful and desire to secure by Letters Patent is:—

35 1. A mechanism of the character described comprising a type carriage, type bars movable therein, a turnable shaft fixed to said type carriage, a projecting arm on said shaft, a rod, a link flexibly connected 40 with said arm and said rod, a key mechanism, and means operatively connected between said key mechanism and said rod, whereby with the operation of said key mechanism said rod will be lifted to cause 45 said link to operate said arm to turn said shaft, as described.

50 2. A device of the character described comprising the combination of a type carriage carrying type bars, a hammer mechanism for operating individual type bars, means for operating said carriage to bring said individual type bars into alinement with said operating mechanism, said last named means comprising a shaft fixed to

55 said carriage, a projecting arm on said shaft, a rod, a link flexibly connected with said arm and with said rod, another shaft, a plurality of curved cams on said shaft engageable with said rod, a key mechanism, and means operatively connected between 60 said key mechanism and said last named shaft whereby with the operation of said key mechanism said last named shaft will be turned to bring said cams into engagement with said rod, as described. 65

3. A device of the character described comprising the combination of a type carriage carrying type bars, a hammer mechanism for operating individual type bars, means for operating said carriage to bring 70 said individual type bars into alinement with said operating mechanism, said last named means comprising a shaft fixed to said carriage, a projecting arm on said shaft, a rod, a link flexibly connected with 75 said arm and with said rod, another shaft, a plurality of curved cams on said shaft engageable with said rod, a key mechanism, means operatively connected between said key mechanism and said last named shaft 80 whereby with the operation of said key mechanism said last named shaft will be turned to bring said cams into engagement with said rod, and means operable between said key mechanism and said type bar operating mechanism whereby with the movement of said key mechanism said type bar mechanism will likewise be operated, as described. 85

4. A mechanism of the character de- 90 scribed comprising type bars, a hammer mechanism for operating individual type bars, such hammer mechanism comprising a hammer pivotally mounted, a catch pivotally mounted in the lower end of 95 said hammer, a dog pivotally mounted independently of said catch and provided with a spring, means for moving said dog to tension said spring and engage said catch, and means for releasing said moving 100 means from said dog to allow said spring to expand, as described.

In testimony whereof I affix my signature in presence of two witnesses.

ORIN BENNETT.
